United States Patent Office

Des. 190,567
Patented June 13, 1961

190,567

AUTOMOBILE WHEEL COVER

George W. Walker, Bloomfield Hills, Mich., assignor to Ford Motor Company, Dearborn, Mich., a corporation of Delaware

Filed Oct. 3, 1960, Ser. No. 62,349

Term of patent 7 years

(Cl. D14—30)

FIG. 1 is a front elevational view of an automobile wheel cover showing my new design;

FIG. 2 is a sectional view taken on the line 2—2 of FIG. 1; and

FIG. 3 is an enlarged partial section taken on the line 3—3 of FIG. 1.

I claim:

The ornamental design for an automobile wheel cover, as shown.
